John Holachek
ATTORNEY

UNITED STATES PATENT OFFICE

SAMUEL T. ALABISO, OF NEW YORK, N. Y.

RAZOR HOLDER

Application filed March 24, 1932. Serial No. 600,875.

This invention relates to new and useful improvements in a razor holder.

The invention has for an object the construction of a razor holder which is characterized by the provision of a clamp element hingedly mounted upon a guard element and arranged in a manner so that a blade may be held therebetween for use in shaving.

It is a still further object of this invention to provide a pair of spaced hooks projecting from the guard element and adapted to engage in side cutouts in the razor blade to accomplish holding of the blade.

Furthermore, as another object of this invention it is proposed to support a spring element upon the rear of the guard element in a manner so that a portion thereof extends through the guard element and is adapted to act against the blade when the latter element is raised for cleaning.

Furthermore, as another object of this invention it is proposed to make provision whereby when the clamp element is pivoted upwards to a raised position the blade moves correspondingly to a horizontal position.

Another one of the objects of this invention is to extend the ends of the spring element in a manner so as to engage against portions of the clamp element and hold the latter pivoted upwards or downwards.

A still further object of this invention is the construction of an article of the class described which is of simple durable construction, dependable in use and efficient in operation and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a razor holder constructed according to this invention.

Fig. 2 is a view similar to Fig. 1 but il-

lustrating the clamp element in a raised position.

Fig. 3 is a view similar to Fig. 1 but illustrating the device with the clamp element completely removed.

Fig. 4 is a perspective view of the razor blade.

Fig. 5 is a perspective view of the spring member used in the device.

Fig. 6 is a sectional view as though taken on the line 6—6 of Fig. 1, but illustrating a modification.

Fig. 7 is a perspective view of the spring member used in Fig. 6.

Fig. 8 is a fragmentary perspective view showing another modification.

Fig. 9 is an underside view of Fig. 8, taken on the line 9—9 of Fig. 8.

The razor holder, according to this invention, comprises a guard element 10 which is formed with a plurality of cutout portions 11 along the bottom edge for the passage of the soap when the device is being used for shaving. A handle 13 is attached upon the rear face of the guard element 10. A pair of hooks 14 projecting to the front of the guard element 10 from the edges thereof. These hooks are adapted to engage cutouts 15 formed in a razor blade back 16 which is connected with a razor blade 16'.

A clamp element 17 is provided with side portions 18 at right angles thereto. These side portions pivotally engage upon pegs 19 projecting from the hooks 14. Small projections 20 from the sides 18 of the clamp element are adapted to rest within cutouts 21 formed in the guard element 10 so that the razor blade 16' may lie flat against the guard element and so that when the clamp 17 is lifted the projections 20 lift the blade along with it.

A spring member is mounted upon the rear of the guard element 10 by rivets or the like and comprises a pair of arms 22 joined by a handle 23. These parts are made from one piece but the handle is turned at right angles to the portions 22 as shown in Fig. 5. A finger 24 is stamped from the handle portion and comprises a spring top. This spring 24 passes through a slot 25 formed in the guard element 10. The ends of the portions 100

22 extend past the edges of the guard element 10 as clearly shown on the drawing and act against the portions 18 from the clamp so as to hold the clamp element either in the lowered position shown in Fig. 1 or the raised position shown in Fig. 2 and to apply pressure on the razor blade.

5 The device, as shown in Fig. 1 is ready for use. To remove the blade after use it is merely necessary to tilt the clamp element upwards 10 and the projections 20 will lift the blade 17 in a similar manner. Fig. 2 shows this position, in which the finger 24 holds the blade down upon the hooks 14. To remove the 15 blade from the hooks 14 the spring member 24 must be manually bent up. The blade is then free to be lifted from the hooks.

20 In the modified form illustrated in Figs. 6 and 7, the free end of the spring 24 is rolled, as indicated by reference numeral 26, so that it is impossible to draw the spring out from the slot 25 by pulling on the handle 23. Bayonet slots 27 are formed upon the portions 22 and are adapted to engage with screws 28 25 rivets or the like projecting from the rear side of the guard element 10. The finger 24 normally urges the blade 16' flat against the guard 10. To remove the blade 16' from the hooks 14 the spring member 24 must be 30 moved so that the bayonet slots 27 are released from the screws 28 and then the spring member may be drawn rearwards to draw in the spring 24 from acting on the blade portion 16. The blade is then free to be lifted.

35 In Figs. 8 and 9 the spring 24' is made shorter and is adapted to engage one end of the pivoted tongue 24^a thereby forcing the other end of the said tongue resiliently over the blade back 16.

40 While I have shown and described the preferred embodiment of my invention, it is to be understood that I do not limit myself to the precise construction herein disclosed and the right is reserved to all changes and modifications coming within the scope of the invention as defined in the appended claims.

45 Having thus described my invention, what I claim as new, and desire to secure by United States Letters Patent is:

- 50 1. A razor holder, comprising a guard element with a pair of rivets or the like on the back thereof, a handle mounted upon said guard element a pair of hooks on the edges of the guard element and projecting to the front 55 for engaging side cutouts in a blade so that the blade is pivotally supported, a clamp element hinged on the sides of said hooks and having lugs engaging behind a blade supported upon said hooks, and a spring member mounted on the rear of the guard element and having a finger portion passing through a slot in the guard element and acting as a stop when the blade is raised so as to nearly be removed from said hooks.
- 60 2. A razor holder, comprising a guard ele-

ment with a pair of rivets or the like on the back thereof, a handle mounted upon said guard element, a pair of hooks on the edges of the guard element and projecting to the front for engaging side cutouts in a blade 70 so that the blade is pivotally supported, a clamp element hinged on the sides of said hooks and having lugs engaging behind a blade supported upon said hooks, and a spring member mounted on the rear of the guard element and having a finger portion 75 passing through a slot in the guard element and acting as a stop when the blade is raised so as to nearly be removed from said hooks, said guard element being formed with a plurality of openings along its bottom edge.

80 3. A razor holder, comprising a guard element with a pair of rivets or the like on the back thereof, a handle mounted upon said guard element, a pair of hooks on the edges of the guard element and projecting to the front for engaging side cutouts in a blade so that the blade is pivotally supported, a clamp element hinged on the sides of said hooks and having lugs engaging behind a 85 blade supported upon said hooks, and a spring member mounted on the rear of the guard element and having a finger portion passing through a slot in the guard element and acting as a stop when the blade is raised 90 so as to nearly be removed from said hooks, said clamp element being provided with end portions engaging against projecting ends from said spring member to hold it in a 95 raised or lowered position.

100 4. A razor holder, comprising a guard element with a pair of screws, rivets or the like, on the back thereof, a handle mounted upon said guard element, a pair of hooks on the edges of the guard element and projecting to the front for engaging side cutouts in a blade so that the blade is pivotally supported, a clamp element hinged on the sides of said hooks and having lugs engaging behind a 105 blade supported upon said hooks, and a spring member mounted on the rear of the guard element and having a finger portion passing through a slot in the guard element and acting as a stop when the blade is raised 110 so as to nearly be removed from said hooks, said guard element being formed with cutouts for receiving the lugs from the clamp element to allow the razor blade to rest flat 115 against the guard element.

120 5. A razor holder, comprising a guard element with a pair of screws, rivets or the like, on the back thereof, a handle mounted upon said guard element, a pair of hooks on the edges of the guard element and projecting to the front for engaging side cutouts in a blade 125 so that the blade is pivotally supported, a clamp element hinged on the sides of said hooks and having lugs engaging behind a blade supported upon said hooks, and a spring member mounted on the rear of the guard ele- 130

ment and acting as a stop when the blade is raised so as to nearly be removed from said hooks, said spring member being made from sheet material, and the handle portion being bent at right angles to the main portion thereof.

6. A razor holder, comprising a guard element with a pair of screws, rivets or the like, on the back thereof, a handle mounted upon said guard element, a pair of hooks on the edges of the guard element and projecting to the front for engaging side cutouts in a blade so that the blade is pivotally supported, a clamp element hinged on the sides of said hooks and having lugs engaging behind a blade supported upon said hooks, and a spring member mounted on the rear of the guard element and having a finger portion passing through a slot in the guard element and acting as a stop when the blade is raised so as to nearly be removed from said hooks, said spring member being formed with bayonet slots engageable upon screws on the rear of said guard plate, and said finger portion having a rolled edge to prevent complete withdrawal from said slot.

7. A razor holder, comprising a guard element with a pair of screws, rivets or the like, on the back thereof, a handle mounted upon said guard element, a pair of hooks on the edges of the guard element and projecting to the front for engaging side cutouts in a blade so that the blade is pivotally supported, a clamp element hinged on the sides of said hooks and having lugs engaging behind a blade supported upon said hooks, and a spring member mounted on the rear of the guard element and having a finger portion passing through a slot in the guard element and acting as a stop when the blade is raised so as to nearly be removed from said hooks, said spring member being formed with bayonet slots engageable upon screws on the rear of said guard plate, and said finger portion having a rolled edge to prevent complete withdrawal from said slot, and the free end of the finger from said spring member being enlarged so that it may not be drawn completely through the slot in the guard element.

50 8. A razor holder, comprising a guard element with a pair of screws, rivets or the like, on the back thereof, a handle mounted upon said guard element, a pair of hooks on the edges of the guard element and projecting to the front for engaging side cutouts in a blade so that the blade is pivotally supported, a clamp element hinged on the sides of said hooks and having lugs engaging behind a blade supported upon said hooks, and a spring member mounted on the rear of the guard element and having a finger portion passing through a slot in the guard element and acting as a stop when the blade is raised so as to nearly be removed from said hooks, said 65 spring member being made from sheet mate-

rial, and the handle portion being bent at right angles to the main portion thereof, said finger portion is hingedly mounted within the said razor holder and is resiliently held by the said spring member.

In testimony whereof I have affixed my signature.

SAMUEL T. ALABISO.
